Primary Examiner — Kevin Rudzinski(74) Attorney, Agent, or Firm — Banner & Witcoff, Ltd.(57) CLAIM

The ornamental design for a display screen with graphical user interface, as shown and described.

DESCRIPTION

The FIGURE is a front view of a display screen with graphical user interface showing our new design. The broken line showing of the text, the tiles, the table, remainder of the user interface, and the remainder of the display screen is for environmental purposes only and forms no part of the claimed design.
